UNITED STATES PATENT OFFICE.

JOHN D. ABRAHAM, OF CINCINNATI, OHIO.

DESIGN FOR A WASHOUT WATER-CLOSET.

SPECIFICATION forming part of Design No. 16,594, dated September 11, 1888.

Application filed July 30, 1888. Serial No. 281,480. Term of patent 7 years.

To all whom it may concern:

Be it known that I, JOHN D. ABRAHAM, a citizen of the United States, residing at Cincinnati, in the county of Hamilton and State of Ohio, have invented and produced a new and original Design for Pedestal Washout Water-Closets, of which the following is a specification, reference being had to the accompanying illustration, forming part thereof.

10 The main features of my design consist in the shape, contour, and surface ornamenta-

tions for a pedestal washout water-closet, as shown in the illustrations herein referred to.

What I claim is—

The design for a pedestal washout water-closet, as herein shown, of the shape, contour, and surface ornamentation as herein set forth.

JOHN D. ABRAHAM.
